UNITED STATES PATENT OFFICE.

EDWIN W. WEBB, OF CHICAGO, ILLINOIS, ASSIGNOR TO STANDARD CAR TRUCK COMPANY, OF CHICAGO, ILLINOIS, A CORPORATION OF NEW JERSEY.

CAR TRUCK.

1,407,452.

Specification of Letters Patent. Patented Feb. 21, 1922.

Application filed November 12, 1921. Serial No. 514,586.

To all whom it may concern:

Be it known that I, EDWIN W. WEBB, a citizen of the United States, residing at Chicago, in the county of Cook and State of Illinois, have invented certain new and useful Improvements in Car Trucks; and I do hereby declare the following to be a full, clear, and exact description of the invention, such as will enable others skilled in the art to 10 which it appertains to make and use the same.

This invention relates to a car truck, and particularly, to a truck such as used for railway cars.

15 Considerable trouble has been experienced in railway trucks, due to the excessive wear of the truck bolster and the side frame bolster columns, especially on the type of the truck in which the bolster has a vertical spring action. It is desirable, therefore, to have the greatest possible area of wearing surface between the bolster and bolster columns.

It is an object of this invention, therefore, 25 to provide a truck structure in which a large area of wearing surface is obtained, particularly, in connection with the type of the side frame now widely used, which has the top or compression member of inverted U-shape 30 in cross section.

It is a further object of the invention to provide this additional wearing surface by extensions projecting from the top and bottom sides of the bolster and to so arrange 35 these projections that they will not interfere with the movement of the bolster or other parts of the truck.

These and other objects and advantages of the invention will more fully appear from 40 the following description made in connection with the accompanying drawings in which like reference characters refer to the same parts throughout the different views, and in which

45 Fig. 1 is a vertical central section through one end of the truck;

Fig. 2 is a vertical section taken on the line 2—2 of Fig. 1, but showing the side frame in end elevation;

50 Fig. 3 is a section taken on the line 3—3 of Fig. 2;

Fig. 4 is a bottom plan view of one end of the bolster; and

55 Fig. 5 is a partial section similar to that shown in Fig. 3, but showing a modification.

Referring to the drawings, the central part of the side frame 1 is shown having the bolster columns 1^a. In the construction of the present truck, these bolster columns are 60 preferably made somewhat wider than usual, the increased width over the other parts of the side frame being clearly indicated in Fig. 3. The side frame has its top portion or compression member of inverted U-shape 65 in cross section, as shown at 1^b. This type of cast steel side frame is now widely used. The bolster 2 extends, as usual, between the bolster columns and is provided at its outer end with the projecting lugs 2^a forming 70 guides or stops to limit the endwise movement thereof. The bolster is formed on its bottom surface with recesses to receive and retain the roller bearings 3 which are, in turn, supported upon the usual spring cap or 75 plate 4 which is, likewise, provided with roller receiving surfaces and intermediate ribs, as clearly shown in Fig. 3. The plate 4 is supported upon a plurality of coiled springs 5 which are, as usual, seated upon 80 the bottom part of the side frame or the spring plank or tie member extending across the same.

The bolster 2 is shown as of box section, the sides of which form the wearing surface for 85 contacting with the bolster columns, and in accordance with the present invention, an upwardly projecting extension 2^b is provided at each side of the bolster which is shown connected to the top thereof by a central reinforcing rib. The extension 2^b is of such width 90 longitudinally of the bolster as to be received in the recess of the U-shaped section 1^b of the side frame. When the truck is being assembled therefore, this extension will be received in said recess, thus giving ample room 95 for the assembling operation. Normally, the extension 2^b will be located so that its top edge will pass below the bottom of the U-shaped section so that there will be no 100 interference with the usual endwise movement of the bolster. In addition to the upwardly projecting extension, the bolster is also provided at each side, with a downwardly projecting extension 2^c forming a 105 continuation of its wearing surface. As shown in Fig. 2, the spring cap 4 has upwardly projecting flanges 4^a at its sides forming the retaining means for the rollers and these flanges are arranged to be disposed inside of the extensions 2^c. The cap or plate 4, however, is, at its end portion, provided

with the usual projecting guide lugs 4^b which embrace the sides of the bolster columns and limit the movement of the plate relatively thereto. The guide lugs are sufficiently spaced to permit about one and one-eighth inches of lateral movement in either direction for the average size truck. It will be noted that the extension 2^e pass down between the guide lugs 4^b and said extensions do not interfere in any way with the movements of the plate or cap 4.

If the bolster columns are not made with extra width, as shown in Figs. 1 and 3, the extensions 2^e can still be provided on the ends of the bolster and the spring plate constructed, as shown at 6 in Fig. 5. In this construction, the lugs 6^a corresponding to the lugs 4^b in Fig. 3, are formed to extend or project inwardly to contact with the sides of the bolster column, thus forming a recess 6^b in which the downward extension 2^e of the bolster is disposed.

From the above description it is seen that applicant has provided a truck with a large extent of wearing surface between the bolster and bolster columns and this additional wearing surface is provided without interfering in any way with the desired movements of the truck parts. As stated, the structure used has the popular design of cast steel truck side frame having the inverted U section at the top. The additional wearing surface provided also does not in any way interfere with the assembling operation. A truck constructed according to the present invention will have a much longer life than one having the smaller wearing surfaces.

It will, of course, be understood that various changes may be made in the form, details and proportions of the parts without departing from the scope of applicant's invention, which, generally stated, consists in the matter shown and described and set forth in the appended claims.

What is claimed is:

1. A car truck comprising a side frame having its compression member of inverted U shape in cross section, and having bolster columns, a bolster having a wearing surface extension projected upwardly at the side thereof and adapted to be received in said U-shaped section of the side frame when the truck is assembled.

2. The structure set forth in claim 1, said bolster also having a downwardly projecting extension at the side thereof forming a continuation of its wearing surface.

3. The structure set forth in claim 1, and means for supporting said bolster for endwise movement, said extension being normally disposed below said U-shaped section to permit endwise movement of the bolster.

4. A car truck having bolster columns

provided with guiding and wearing surfaces, and a bolster having wearing surfaces co-operating therewith, said latter surfaces comprising downwardly projecting extensions at each side of said bolster projecting below the body of the bolster between the bolster columns.

5. A car truck comprising a side frame having bolster columns, a bolster movable therebetween and having extensions disposed between the bolster columns and projecting below the line of the main body of the bolster adjacent said columns, said projections forming extended wearing surfaces adapted to contact with the wearing surfaces of the bolster columns, a spring supported roller carrying plate for supporting said bolster, the sides of said plate being disposed between said extensions and below said line.

6. A car truck having bolster columns provided with guiding and wearing surfaces, and a bolster of box section having wearing surfaces co-operating therewith and comprising a downwardly extending projection at each side of said bolster which projects below the bottom of said box section.

7. A car truck comprising a side frame having bolster columns, a bolster vertically and longitudinally movable therebetween having wearing surfaces at the sides thereof comprising downwardly projecting extensions disposed between the bolster columns and extending below the main side walls of the bolster body in the cross plane of said columns, a plurality of springs supported on the side frame, a cap plate supported on said springs, and a plurality of rollers supported on said cap plate for supporting said bolster, said cap plate having upwardly extending flanges at its side portions for retaining the rollers, said flanges being disposed between said downwardly projecting extensions of the bolster whereby endwise movement of the bolster is permitted.

8. A car truck comprising a side frame having its upper member of inverted U shape in cross section and having bolster columns, a bolster vertically and longitudinally movable between said columns having wearing surfaces at its sides comprising upwardly and downwardly projecting extensions, a spring cap carrying rollers for supporting said bolster and having guide lugs at its ends embracing the sides of said bolster columns, the upwardly projecting extensions of the bolster being adapted to enter said U-shaped section when the truck is assembled and the downwardly projecting extensions of the bolster being adapted to pass between said guide lugs on the spring cap.

In testimony whereof I affix my signature.

EDWIN W. WEBB.
